UNITED STATES PATENT OFFICE.

SOLOMON HIMMEL, OF BALTIMORE, MARYLAND.

DISPLAY-RACK.

1,300,167.

Specification of Letters Patent.

Patented Apr. 8, 1919.

Application filed April 9, 1915. Serial No. 20,267.

To all whom it may concern:

Be it known that I, SOLOMON HIMMEL, a citizen of the United States, residing at Baltimore, in the State of Maryland, have 5 invented new and useful Improvements in Display-Racks, of which the following is a specification.

This invention is an improved display rack of the rotary inclosed type, in which the 10 articles to be displayed, are carried by a suitable rack member mounted to rotate within a case or cabinet.

One of the objects of the invention is to provide a case or cabinet with a rack member, 15 mounted to rotate upon a horizontal axis, and particularly adapted for the display of garments, although not limited in this particular. A further object is to provide means for automatically returning the 20 rack member to a predetermined position within the case or cabinet, after it has been partially rotated and released. A further object is to provide means for locking the rack member at any desired point in its rotation.

The invention will be hereinafter fully set forth and particularly pointed out in the claims.

In the accompanying drawing:—

30 Figure 1 is a front elevation of a display rack constructed in accordance with my invention. Fig. 2 is a transverse sectional view thereof. Fig. 3 is a detail view illustrating the locking device. Fig. 4 is a detail view of the device for maintaining the rack member in its normal position.

Referring to the drawing, 10 designates a case or cabinet of any preferred construction, the same being illustrated as comprising 40 a base and top united by end panels 11, and a back panel 12, all of glass, and provided with a front opening closed by sliding doors 13, all of well known form.

The rack or article supporting member, 45 comprises a body of approximately inverted U-shape formed of the garment supporting rod 14 having depending supporting members 15 attached to its ends, said supporting members being pivotally attached to tubular standards or supports 16 secured to the base of the case or cabinet 10. The standards 16 are located as near to the end panels 11 as practicable, but spaced a sufficient distance from said end panels to permit the doors 50 13 to pass between the supports and end panels when said doors are opened. The

lower ends of the depending supporting members 15 are enlarged to provide weighted portions 17, which serve to normally maintain the supporting members in a vertical position, with the supporting rod sustained in a middle position between the standards 16. In order to permit varying of the weight of the portions 17, to conform to difference in weight of garments of different styles or characteristics, the enlarged portions 17 are provided with openings 18 arranged in pairs, to receive depending lugs or extensions 19, of removable weights 20. In addition to their function of returning the rack to its normal position after being rocked on its pivotal supports and then released, the weighted portions 17 also serve to counterbalance the weight of the clothing supported by the rack. Said weight is so counterbalanced that the rack is automatically returned to normal position without shock, and the use of stops to limit the pivotal movement of the rack is rendered unnecessary.

In operation, when it is desired to inspect or remove a garment supported by the rod 14, the operator grasps said rod and swings the same forward upon the pivot rods 21, thus bringing said rod to the front 85 of the case, where all of the garments supported thereby may be readily inspected, and the desired selection conveniently made. In order to maintain the rod 14 in its forward position, one of the standards 16 is 90 provided with an arcuate locking member 22 having a slot curved on a radius concentric with the pivot rod 21, said rod having passed therethrough the threaded stem 23 of a clamping member carried by the contiguous rod or supporting member 15. A clamping nut working upon the stem 23 serves to lock the rack member in any adjusted position. When the rack member is released, and free to rock upon the pivot 100 rods 21, the garment supporting rod is returned to its normal position within the case, through the action of the weighted portions 17, the return movement being wholly automatic. Should the weighted portions 17 be too light to return the rack to its normal position within the case, by reason of the garments too nearly approximating the same weight as said weighted portions, weights 20, of sufficient size to secure 110 the desired result are attached to said portions 17.

Having thus explained the nature of my invention, and described an operative manner of constructing and using the same, although without attempting to set forth all of the forms in which it may be made, or all of the forms of its use, what I claim is:—

- 5 1. A display rack of the character described comprising a garment supporting rod of substantially inverted U-shape, spaced apart standards to which the depending members of said rod are pivotally connected, and counter-balancing means carried by the lower ends of said depending members for automatically returning said rod to a neutral position without shock after being rocked from said position and released.
- 10 2. A display rack of the character described comprising a rack member provided with a garment supporting rod having depending portions, and means engaging said depending portions between the ends thereof to rotatably support the rack member, the lower free ends of said depending portions being weighted to return the rack member to a predetermined position when rotated upon its support and released, and weights removably attached to said depending portions.
- 15 3. A display rack of the character described comprising a rack member provided with a garment supporting rod, means for pivotally supporting said rack member to permit the same to swing freely at all times, means for automatically returning said rack bar to a predetermined position when rocked from its normal position and released, and means for temporarily holding said rack member against rotation under the action of said automatic means.
- 20 4. A display rack of the character described comprising a rack member provided with a garment supporting rod, means for pivotally supporting said rack member to permit the same to swing freely at all times, means for automatically returning said rack bar to a predetermined position when rocked

from its normal position and released, means for temporarily holding said rack member against rotation under the action of said automatic means, said means consisting of a clamp member attached to said supporting means, and a complementary member carried by said rack member to coöperate with the clamp member.

5 5. The combination with a case or cabinet of standards located within the case or cabinet contiguous to the end walls thereof, to provide clearance between the standards and the ends of the case to accommodate sliding doors, a garment supporting rod having depending supporting members pivotally connected to said standards, and counter-balancing means carried by the lower ends of said depending members for automatically returning said rod to a neutral vertical position without shock after being rocked from a position within the case.

6 6. A display rack of the character described comprising spaced apart standards, a rack member provided with a garment supporting rod having depending portions provided with weighted lower ends, pivot pins attached to said depending portions and rotatably engaging said standards, and means for locking said rack member against pivotal movement.

7 7. A display rack of the character described comprising spaced apart standards, a rack member provided with a garment supporting rod having depending portions provided with weighted lower ends, pivot pins attached to said depending portions and rotatably engaging said standards, and weights removably engaging said weighted ends.

In testimony whereof I have hereunto set my hand in presence of two subscribing witnesses.

SOLOMON HIMMEL.
